FIGURE 1 is a perspective view of a vehicle instrument panel showing my new design;

FIGURE 2 is a front elevational view;

FIGURE 3 is a side elevational view taken generally along the plane indicated by line 3—3 of FIGURE 2;

FIGURE 4 is a plan view taken generally along the plane indicated by line 4—4 of FIGURE 2;

FIGURE 5 is a sectional view taken generally along the plane indicated by line 5—5 of FIGURE 3;

FIGURE 6 is a sectional view taken generally along the plane indicated by line 6—6 of FIGURE 2; and

FIGURE 7 is a sectional view taken generally along the plane indicated by line 7—7 of FIGURE 3.

The dominant features of my design reside in the full line portions of the drawings, and the seat and steering wheel shown in broken lines in FIGURE 1 are only included for illustrative purposes.

I claim:

The ornamental design for a vehicle instrument panel, substantially as shown and described.
